UNITED STATES PATENT OFFICE.

SAMUEL BURNHAM, OF ROCHESTER, NEW YORK.

HEEL FOR BOOTS AND SHOES.

No. 892,647.

Specification of Letters Patent.

Patented July 7, 1908.

Application filed January 24, 1908. Serial No. 412,474.

To all whom it may concern:

Be it known that I, SAMUEL BURNHAM, of Rochester, in the county of Monroe and State of New York, have invented a new and useful Improvement in Heels for Boots and Shoes, which improvement is fully set forth in the following specification and shown in the accompanying drawings.

This invention relates to certain new and useful improvements in heels for boots and shoes, and it has for its objects among others to provide a simple and improved heel made up in parts or sections, the lower part, that subjected to wear in walking, being made removable so as to be replaced by a new portion when worn, yet rigidly held in position so as to prevent accidental displacement. The lower or removable part may be made in one, two or more sections, the object of which is to provide for the removal of that portion only of the heel that is badly worn and the replacing it by a new perfect portion. As it is sometimes the tip of the heel portion and at other times the outside of the heel near the tip that is most worn, the advantages to be gained by making the removable portion in sections will be apparent and readily appreciated.

Other objects and advantages of the invention will hereinafter appear and the novel features thereof will be particularly pointed out in the appended claims.

The invention, in its preferred forms, is clearly illustrated in the accompanying drawings which, with the numerals of reference marked thereon, form a part of this specification and in which

Figure 1 is a side elevation of a portion of a shoe showing the improved heel applied thereto. Fig. 2 is a substantially central vertical longitudinal section through the heel. Fig. 3 is a bottom plan of the heel with the lower, or removable portion detached. Fig. 4 is a section on the line 4—4 of Fig. 2 looking down. Fig. 5 is a top plan of the removable portion detached and formed in sections. Fig. 6 is a similar view showing another form of removable portion. Fig. 7 is a detail, partly in section and partly in elevation, the section being on the line 7—7 of Fig. 6.

Like numerals of reference indicate corresponding parts throughout the several views.

Referring to the drawings 1 designates a

portion of a shoe of any well known or preferred form of construction.

2 is the upper portion of the heel, made up of any desired number of layers or lifts of leather or other suitable material, as seen in Fig. 2, and this portion is designed to be secured to the sole of the shoe in any of the well known ways, not necessary to herein illustrate. Next below the portion 2 is the portion 3 which is preferably of metal in the form of a hollow shell, as seen best in Fig. 2, having preferably a marginal flange 4 around its upper edge, as seen in said Fig. 2, for the purpose of affording a better support for the upper portion 2 of the heel. This shell is provided with openings 5, in this instance shown as two in number and through which pass ordinary wood screws 6, as seen in Figs. 2 and 3, the said screws, as seen in Fig. 2, passing into one or more of the lifts or layers of the upper portion 2 of the heel.

Mounted to slide within the shell and upon the bottom thereof is a plate 7 having upon opposite sides notches 8 within which screws or other securing means 6 are received, as seen best in Fig. 4. This plate is actuated by a spring 9 at the point of the shell, the said spring finding a bearing at one end against the end wall of the shell and at the other end against a wall 10 formed by bending up a portion of the movable plate 7 and forming a housing 11 for the spring, the end 12 of said housing forming a stop to engage the end wall of the shell to limit the inward movement of the movable member, as will be clearly understood upon reference to Figs. 2 and 4.

The bottom wall of the plate 3 is provided with a plurality of perforations 13, shown in Fig. 3 as being six in number, although it is evident that this number may be varied under varying circumstances and conditions. The object thereof will soon be made apparent. The movable plate is provided with a plurality of perforations 14, in this instance shown as six in number, for coöperation with the perforations in the bottom wall of the shell. The movable plate may be guided in any suitable manner and held against vertical displacement, in this instance being shown as movable beneath a bar or member 15, extending lengthwise of the shell and over the movable plate, the said bar or member being held in position by a lug 16 extending upward from the bottom of the shell and

through a longitudinal slot 17 in the movable plate, a suitable key 18 being employed, as seen in Figs. 2 and 4, to hold the bar or member 15 in place, it being understood that 5 there is sufficient room between the said bar or member and the bottom wall of the shell to permit the free and easy movement of the plate 7.

The plate 7 has a projecting portion or lug 10 19 projecting through an opening in the end 20 of the shell, as seen best in Fig. 2, the said projecting member having a portion 21 which extends beneath the flange 4 of the shell, as seen in said Fig. 2, to form a guide 15 therefor and prevent its upward displacement.

In Fig. 3 there are shown projections 22 rigid with the shell upon opposite sides of the projecting part 19 to shield the same and 20 to prevent accidental inward movement of the movable plate which might result in loosening the removable part of the heel.

23 is the lower or removable portion of the heel, that which comes in contact with the 25 ground and which is subjected to wear in walking. This may be made up of a single piece or any desired number of layers, as seen in Figs. 1 and 2, or, as seen in Fig. 6, 30 formed of two parts 24 and 25 separable along the inclined line 26, as seen in Fig. 5, composed of the three parts 27, 28 and 29 separable along the lines 30 and 31. This lower portion of the heel is provided with a plurality of pins firmly secured therein, as 35 for example as shown in Fig. 7 wherein the pin 32 is shown as having a screw threaded end 33 by which it may be screwed into the leather, having a slot 34 if desired for the application of a screw driver or like implement. When the lower part is made in one 40 piece, three of such pins ordinarily will be all that will be required. When composed of two or three parts, as seen in Figs. 5 and 6, six pins are preferably employed, as seen in 45 said views. When of two parts three pins are provided in each part. When of three parts, two pins in each part, the pins in both instances being disposed in the same position relatively to each other so as to properly 50 engage the perforations in the bottom of the shell and in the movable plate. The pins are notched, as shown at 35, see Fig. 7, for a purpose which will soon be made apparent.

In practice, the upper portion 2 of the heel 55 being fixedly secured to the shoe and the shell 3 secured to said upper portion, by pressing inward upon the projecting portion 19 of the movable plate, the latter is moved toward the point of the heel, against 60 the tension of the spring 9, so that the perforations of the plate and of the shell are brought coincident with each other, the notches 8, which receive the securing means 6, permitting of said movement, and the end 65 walls thereof serving to limit the movements

of the plate in both directions, as will be readily understood upon reference to Fig. 4. The lower portion or member 23 is then placed in position, with its pins 32 passed through the openings in the bottom of the 70 shell and in the plate, and when thus in position pressure is removed from the projecting portion 19, when the spring 9 forces the plate toward the front of the heel, when the rear walls of the openings in the plate engage in the notches 35 of the pins and securely lock the lower portion against removal. The forward openings in the plate are shown in Fig. 4 as open at their forward ends but this is not necessary. 75 80

From the above it will be seen that when the lower portion becomes worn it can be readily removed by pressing inward on the projection 19, which forces the movable plate to the rear, and when the perforations 85 of the plate and shell are coincident, the lower member 23 can be easily and quickly removed and a new one substituted therefor. When the lower member is made in sections, as in Figs. 5 and 6, any one section thereof 90 may be removed and a new section substituted, without replacing the whole of the lower member.

Modifications in detail may be resorted to without departing from the spirit of the invention or sacrificing any of its advantages. 95

What is claimed as new is:—

1. A heel having its tread portion formed in sections, means projecting from each section, and a slidingly mounted member engageable with all of said projections. 100

2. A heel having a sectional detachable tread portion, a fixed portion, projections on each of the sections of said portion, and an intermediate movable member for engaging 105 all of said projections and holding the detachable tread portion in place.

3. A heel having a sectional tread portion, projections on each of the sections, a fixed portion and a sliding member adapted to 110 simultaneously engage all of said projections and hold the removable tread portion in place.

4. A heel having a detachable tread portion in sections each section provided with 115 pins, and a fixed portion carrying a movable member adapted to engage said pins and hold the removable portion in place and means for holding said member from displacement. 120

5. A heel comprising an upper portion, a hollow shell secured thereto, a sliding member in said shell, and a detachable lower portion in independent sections having means engaged by said sliding member and means 125 for holding said member from displacement.

6. A heel comprising an upper portion, a hollow shell secured thereto, a sliding member in said shell, and a detachable lower portion in independent sections having means 130

engaged by said sliding member, said lower portion being formed in sections and means for holding said member from displacement.

7. A heel comprising an upper portion, a hollow shell secured thereto, a sliding member in said shell, a detachable lower portion in independent sections each having means engaged by said sliding member, means for moving the said member in one direction, and 10 a spring for moving it in the opposite direction and means for holding said member from displacement.

8. A heel having a detachable lower portion in independent sections, an upper portion, an intermediate hollow shell, a movable member within said shell, means for guiding said member and holding it from displacement, and means on each of the sections of the lower portion engaged by said movable 20 member.

9. A heel having a detachable lower portion in independent sections, an upper portion, an intermediate hollow shell, a movable member within said shell, means for guiding said member and holding it from displacement, means on each of the sections of the lower portion engaged by said movable member, said movable member having a projecting portion, and a spring for moving it 30 outward.

10. A heel having a detachable lower portion, an upper portion, an intermediate hollow shell, a movable member within said shell, means for guiding said member and holding it from displacement, means on the lower portion engaged by said movable member, said movable member having a projecting portion, a spring for moving it outward, and means forming a shield for said projecting 40 portion.

11. A heel having a detachable lower portion in independent sections, an upper portion, an intermediate hollow shell, a movable member within said shell, means for guiding said member and holding it from displacement, means on each of the sections of the lower portion engaged by said movable member, said movable member having a projecting portion, a spring for moving it outward, 50 means for preventing accidental inward

movement of said movable member and a housing for said spring.

12. A heel having a detachable lower portion, an upper portion, an intermediate hollow shell, a movable member within said shell, means for guiding said member and holding it from displacement, means on the lower portion engaged by said movable member, said movable member having a projecting portion, a spring for moving it outward, 60 a housing for said spring, and means forming a shield for said projecting portion.

13. A heel having a detachable lower portion of independent sections each provided with upwardly projecting pins having notches, 65 a shell disposed above said lower portion, a member slidably mounted within said shell for coöperation with said pins and adapted to engage said notches and means for preventing accidental inward movement of said member.

14. A heel having a detachable lower portion of independent sections each provided with upwardly projecting pins having notches, 75 a shell disposed above said lower portion, a member slidably mounted within said shell for coöperation with said pins and adapted to engage said notches, a spring for moving said sliding member in one direction, and means projecting from said member for moving it in the opposite direction and means for preventing accidental inward movement of said member.

15. A heel having a detachable lower portion with upwardly projecting pins having 85 notches, a shell disposed above said lower portion, a member slidably mounted within said shell for coöperation with said pins and adapted to engage said notches, a spring for moving said sliding member in one direction, 90 means projecting from said member for moving it in the opposite direction, and a shield for said projecting means.

In witness whereof, I have hereunto set my hand in the presence of two subscribing witnesses.

SAMUEL BURNHAM.
